UNITED STATES PATENT OFFICE.

MORRIS GURTOV, OF NEW YORK, N. Y.

GAME DEVICE.

1,218,398.

Specification of Letters Patent.

Patented Mar. 6, 1917.

Application filed August 5, 1916. Serial No. 113,259.

To all whom it may concern:

Be it known that I, MORRIS GURTOV, a citizen of the United States, and a resident of New York, in the county of New York and State of New York, have invented certain new and useful Improvements in Game Devices, of which the following is a specification.

My invention relates to toys and games for children, and the main object thereof is to provide a device which may be used as a doll or toy, shown as an effigy of a bear although it may represent other animals, and which may be used at will as a game device in conjunction with one or more playing balls.

My invention is fully described in the following specification, of which the accompanying drawings form a part, in which like characters refer to like parts in each of the views, and in which:—

Figure 1 is a view of my invention in use as a game device; and

Fig. 2 is a view thereof, partly in central vertical section.

Referring to the drawings 3 represents an effigy of a bear consisting of a solid body member 4 covered with fabric of a woolly or hairy character and the head 5, arms 6, and legs 7 of which may be formed of soft material such as cotton or any suitable equivalent.

The body member 4 is provided with a passage 8 therethrough from front to rear and preferably although not necessarily rearwardly and downwardly inclined, frames 9 being provided at the orifices, front and rear, of a durable material, and it will be noted that the passage 8 is lined with fabric as shown at 10.

The figure may be used as a doll in the usual manner and, when it is desired to utilize the same as a game device, all that is necessary is to prop the same in a substantially vertical position, as against a wall or an article of furniture, with the front toward the player, shown at 11 as a child, who strives to throw a ball into the passage 8 whence it emerges at the rear of the figure and may be retrieved to again try to throw it through the figure.

The passage is shown with square frames 9 but any desired shape thereof may be substituted which permits the entry of a ball into the passage, and I prefer to make the openings through the frames conform to the shape of the passage and of such dimensions as to permit the entry of a ball though not in too easy a manner.

My invention is very simple in construction and use, and children will derive much enjoyment therefrom, as may adults as well, and I do not confine myself to any particular shape of the device, as many shapes other than that shown may be readily conceived.

Having fully described my invention, what I claim as new, and desire to secure by Letters Patent, is:—

A device of the class described, comprising a body of unyielding material having a passage therethrough downwardly inclined from front to rear, and a covering of yielding material formed to represent an animal, said passage being for the reception and guidance of a thrown ball.

MORRIS GURTOV.
